SOUND REPRODUCING APPARATUS

Frank Freimann and John L. Friesner, Fort Wayne, Ind., assignors to Electro-Acoustic Products Company, Fort Wayne, Ind., a corporation of Illinois

Application May 22, 1935, Serial No. 22,886

11 Claims. (CL 274—2)

The present invention relates to an improvement in sound reproducing apparatus of the character employing a sound record of the disc type, and more particularly to a novel arrangement in a carrying case whereby the record supporting platen may be removed and conveniently and firmly secured in a compartment provided therefor.

An object of the present invention is to provide 10 an improved carrying case for sound reproducing apparatus of the type employing sound records of the disc type.

Another object of the invention is to provide 15 within a carrying case of the character described, a novel form of support for a demountable record supporting platen.

A further object of the invention is to provide 20 a novel form of platen holding means for apparatus of the character disclosed, wherein the record holding means in addition to firmly supporting the platen will also hold a separate baffle of the type disclosed in our copending application entitled Loud speaker mounting, filed May 22, 1935, and identified by Serial Number 22,887.

Other objects and advantages of the invention 25 will be in part evident to those skilled in the art to which this invention pertains and in part pointed out as the description thereof proceeds.

For a better understanding of the invention, 30 reference should be had to the accompanying drawing wherein there is shown, by way of illustration and not of limitation, preferred embodiments thereof.

In the drawing, wherein like numerals refer to 35 like parts—

Figure 1 is a perspective view of a carrying case of the character contemplated by this invention with a portion broken away to reveal one embodiment of the invention.

Figure 2 is an end elevation of the carrying case illustrated in Figure 1, with a portion thereof broken away to more clearly show the manner of securing the demounted record supporting platen.

Figure 3 and 4 are fragmentary views similar to Figure 2, showing arrangements for supporting a record platen and a separate loud speaker baffle, and

Figure 5 shows a modified form of the platen supporting means contemplated by this invention.

For the purpose of illustrating this invention we have, in the drawing, shown a carrying case of the type contemplated in a copending application filed by Frank Freimann, August 18, 1934,

entitled Carrying case and identified by Serial Number 740,448.

In the drawing, the numeral 10 designates a carrying case that is adapted to enclose a picture projecting lantern, a loud speaker and a suitable thermionic amplifying means, all of which are adapted to operate in conjunction with an electromagnetic sound reproducing apparatus. The carrying case 10 has a cover 11 that can be secured thereover to enclose the sound reproducing apparatus mounted externally upon the top of the carrying case 10. The sound reproducing apparatus, in one form, consists of a suitable motor driven means having a vertically disposed shaft 12 upon which a record supporting platen 13 may be mounted. Cooperating with a sound record upon the supporting platen 13 there is an electromagnetic pick-up device 14 which is carried by a supporting arm 15. The supporting arm 15 is mounted with a swivel connection upon a pedestal 16 so that when the pick-up device 14 is placed in the sound track of the record it will generate sound frequency currents which can be reproduced by a suitable loud speaker. In the present instance such a loud speaker, designated by the numeral 17, is shown as mounted in the side of the carrying case 10. The picture projecting apparatus, previously referred to as contained within the carrying case 10, is mounted upon a hinged panel 18 at one end of the carrying case in such a manner that when this hinged panel is swung outwardly the picture projecting apparatus will move into a position for the projection of a picture upon a screen located in front thereof.

For convenience the carrying case 10 is made as narrow as is practicable to contain the picture projecting apparatus, the thermionic amplifying means and the loud speaker. Therefore, in order that the sound reproducing apparatus may be rendered adaptable to the reproduction of programs from records having a diameter greater than the width of the carrying case, the record supporting platen 13 is made removable from its driving shaft 12. When the record supporting platen 13 is thus removed from its horizontal position upon the driving mechanism it is carried in a narrow vertical compartment 19 at one side of the carrying case 10 where the cover 11 may be secured thereover. Under these conditions the supporting arm 15 will be secured in a stable position, in the manner disclosed and claimed in the aforesaid application, filed by Frank Freimann. The carrying case with the entire equipment can then be transported con-

veniently from one place to another. For this purpose the cover 11 is provided with a handle or grip 20, as shown in Figure 2 of the drawing.

As illustrated in the drawing, the sound record supporting platen 13 has a central hub 21 with an axially extending aperture 22 through which the motor driven shaft 12 may project to center the sound record as is well known. In addition to this axially extending hole 22 the hub 21 is provided, in one embodiment of this invention, with a transversely extending aperture 23 into which a supporting pin 24 is adapted to project. In order to provide for a narrow compartment 19 for the removed platen 13 we provide a notch 25 which extends downwardly from the top edge of a compartment forming partition 26. This notch 25 is made of sufficient width to receive the hub 21 of the record supporting platen 13 and it is deep enough to hold the platen 13 at a point where the cover 11 will close thereover. The vertically extending pin 24 is shown as projecting upwardly in the center of the notch 25 so that when the transversely extending aperture 23 of the hub 21 is placed thereover the hub 21 of the record supporting platen 13 will be centered within the notch 25 of the partition 26. When the pin 24 thus located in the notch 25 is inclined at a slight angle, as illustrated in Figure 2 of the drawing, it will exert a wedging action upon the hub 21 and cause the flanged rim of the record supporting platen 13 to be pressed firmly against the side of the compartment forming partition 26. This will firmly secure the platen 13 upon the partition 26 and prevent a rattling thereof during transportation of the apparatus from one place to another.

If the carrying case is equipped with a removable loud speaker 17 and a separate baffle forming member, as contemplated in an application filed by us concurrently herewith, the pin 24 may be inclined at an opposite angle, as shown in Figure 3 of the drawing. This will cause the record supporting platen 13 to be urged away from the compartment forming partition 26. When the pin 24 is inclined in this manner and a separate baffle forming member 27 is placed within the compartment 19, as illustrated, both the platen and the baffle forming member 27 will be snugly held against vibration within the compartment 19 of the carrying case.

In Figure 4 of the drawing, there is shown a variation of the last above arrangement, in which a pin, designated by the numeral 28, is disposed within the compartment 19 and out of alignment with the notch 25, so that it will engage the aperture 23 in the hub 21 when the separate baffle forming member 27 is disposed between the baffle forming partition 26 and the record supporting platen 13.

In each of these last two arrangements the disposition and the inclination of the pins 24 and 28 will be such that a wedging action will be produced in one direction or another to firmly hold the platen 13 and the separate baffle forming member 27 against one of the side walls of the compartment 19.

In Figure 5 of the drawing, there is illustrated an embodiment of the invention, wherein instead of a pin 24 or a pin 28 the notch 25 is provided with a member 29 having upwardly extending spaced portions 30 which are adapted to engage a groove 31 that extends completely around the outside of a hub 32 upon the record supporting platen 13. In this embodiment it is contemplated that the upwardly projecting portions 30 of the

member 29 may be inclined at one angle or another to provide for a wedging action similar to that previously described in connection with pins 24 and 28.

While we have, for the sake of clearness and in order to disclose our invention so that the same can be readily understood, described and illustrated specific devices and arrangements, we desire to have it understood that this invention is not limited to the specific means disclosed, but may be embodied in other ways that will suggest themselves to persons skilled in the art. It is believed that this invention is new and it is desired to claim it so that all such changes as come within the scope of the appended claims are to be considered as part of this invention.

Having thus described our invention, what we claim and desire to secure by Letters Patent is—

1. In a carrying case for sound reproducing apparatus of the type employing sound records of the disc type, the combination of a detachable record supporting platen having a central hub for connection with a driving mechanism, a partition within said carrying case forming a compartment into which said record supporting platen may be disposed when detached from said driving mechanism, and means located upon a wall of said compartment engaging the hub upon said platen for securing said platen upon said wall of the compartment.

2. In a carrying case for sound reproducing apparatus of the type employing sound records of the disc type, the combination of a detachable record supporting platen having a central hub through which a driving shaft may pass, a vertically disposed partition within said carrying case forming a compartment into which said record supporting platen may be disposed when detached from said vertical shaft, and means located upon a wall of said compartment engaging the hub upon said platen for securing said platen against said wall of the compartment.

3. In a carrying case for sound reproducing apparatus of the type employing sound records of the disc type, the combination of a detachable record supporting platen having a central hub by which it may be attached to a driving shaft, a partition within said carrying case forming a compartment into which said record supporting platen may be disposed when detached from said shaft, and means carried by said partition engaging the hub upon said platen for securing said platen against said partition.

4. In a carrying case for sound reproducing apparatus of the character employing records of the disc type, the combination of a removable record supporting platen, a compartment in said carrying case for said record supporting platen when said platen is removed from its driving means, said record supporting platen having a central hub, and a support upon a wall of said compartment adapted to engage said hub and wedge said platen against a wall of said compartment.

5. In a carrying case for sound reproducing apparatus of the character employing records of the disc type, the combination of a removable record supporting platen, a compartment in said carrying case for said record supporting platen when said platen is removed from its driving means, said record supporting platen having a central hub with a transversely extending hole therein, and an upwardly extending pin located upon a wall of said compartment adapted to pro-

ject into the transversely extending hole in said hub and secure said platen against said wall.

6. The combination set forth in claim 5 where-
in the supporting pin is inclined at a slight angle
so as to draw the record platen tightly against
the surface of said wall when the hub is forced
thereupon.

7. In a carrying case for sound reproducing ap-
paratus of the character employing records of
the disc type, the combination of a removable
record supporting platen, a compartment in said
carrying case for said record supporting platen
when said platen is removed from its driving
means, said record supporting platen having a
central hub with a support engaging groove ex-
tending therearound, and a support upon a wall
of said compartment adapted to engage said
groove and secure said platen against said wall.

8. The combination set forth in claim 7 where-
in the groove engaging support is inclined at a
slight angle so as to hold the record platen
against a wall of said compartment when the
hub is forced thereupon.

9. In apparatus of the character described, the
combination of a sound record supporting platen
having a central shaft engaging hub, said hub
having a special support engaging configuration,
a compartment forming partition having a notch
extending into its outer edge into which the hub
of said platen may be disposed when the platen
is placed edgewise in said compartment, and

means located in said notch adapted to cooperate
with the support engaging configuration of said
hub to secure said platen firmly and securely
against said partition.

10. In apparatus of the character described, 5
the combination of a sound record supporting
platen having a driving shaft engaging hub, said
hub having a support engaging groove there-
around a vertically disposed compartment forming
partition having a notch extending down- 10
wardly from its top edge into which the hub of
said platen may be disposed when the platen is
placed edgewise in said compartment, and a pair
of spaced members located in said notch adapted
to engage the groove around said hub and secure 15
said platen firmly and securely within said com-
partment.

11. In apparatus of the character described,
the combination of a sound record supporting
platen having a driving shaft engaging hub, said 20
hub having a support engaging opening, a ver-
tically disposed compartment forming partition
having a notch extending downwardly from its
top edge into which the hub of said platen may
be disposed when the platen is placed edgewise 25
in said compartment, and a projecting pin located
in said notch adapted to cooperate with the open-
ing in said hub to secure said platen firmly and
securely within said compartment.
